COMBINATION SEMI-RIGID STORAGE CONTAINER AND DRUM LINER

Thomas W. Winstead, Baltimore, Md., assignor to Hedwin Corporation, Baltimore, Md., a corporation of Maryland

Filed Mar. 24, 1959, Ser. No. 55,147

Term of patent 14 years

(Cl. D58—17)

FIGURE 1 is a perspective view of a combination semi-rigid storage container and drum liner illustrating my new design;

I claim:

The ornamental design for a combination semi-rigid storage container and drum liner, as shown.
